United States Patent Office.

R. B. HUGUNIN, OF CLEVELAND, OHIO.

Letters Patent No. 95,350, dated September 28, 1869.

IMPROVED SASH-HOLDER.

The Schedule referred to in these Letters Patent and making part of the same.

Be it known that I, R. B. HUGUNIN, of Cleveland, Ohio, have invented a new and useful Improvement in the Arrangement of "Rollers and Springs" for "Window-Sash Supporters," of which the following is a specification.

Nature of Invention.

This invention, in the first place, consists in the arrangement of elastic rollers, with one or more small rollers embedded or pressed into the elastic covering of the former, and there permanently secured, for the purpose of creating and maintaining a positive and uniform friction, and smoothness of movement, under a moving-pressure.

Description of Accompanying Drawings.

Figure 1 is a side elevation of plate, with compressed rollers and springs, embracing the features of my invention.

Figure 2 is a plan view of the same.

Figure 3 is a view of the plate, with the rollers and springs removed, &c.

General Description.

A is the lower half of the plate used for compressing, confining, and supporting the rollers.

B is the upper half of plate A.

This plate A B is made in halves, to facilitate casting, with journal-rests, &c.

C C' are journal-rests in plate A, for large and small rollers.

D and D', elastic rollers.

E and E', &c., journals of elastic rollers.

F, small roller, permanently compressed into the elastic rollers, and then forced down to its natural position, (the rests C and C'), and secured there by the plate A B.

It will be observed, this permanent compression of the small roller into the large ones compels them all to move uniformly together, and gives to them a positive and uniform supporting-power, independently of any outside friction or pressure.

G and G' are common wood-screws, used to secure the plate A B to the sash.

H and H', springs, used under the ends of the plate A B, and compressed between the plate and sash by the screws G and G'.

I is the window-sash.

In operation, the rollers D, D', and F, are put into their proper position in plate A by compression, and the plate B placed over them and secured.

The mortise having been made in the edge of the sash, to receive the plate A B, &c., and the pieces of

rubber or springs H and H' having been laid in their proper places, the plate A B and the confined rollers are placed into position, and secured by the screws G and G'.

One of these "supporters" is put in on each side of the sash.

The sash is put into the window by placing one edge against the casing, and with a chisel, or other flat tool, compressing the rollers, and forcing in the other edge, &c.

If there be but little room between the sash and casing, the yielding of the springs H and H' and elastic rollers D and D' will readily allow the sash to enter.

When the sash shrinks away from the casing, the compressed springs H and H' will force the plate outward enough to take up this shrinkage.

The arrangement of the compressed rollers D and D' and F may be continued in number so as to embrace several of each, or only one of each, in one plate, as desired or required.

The plate A B can also be cast in one piece, if desired, and the holes for the journals drilled in it. The compression or adjusting of the rollers, however, would not be so convenient this way.

Small bent metal clasps may be used to hold the plates A and B together till put into the sash.

I do not claim the use of elastic or non-elastic rollers, nor the combination of the two for such supporters, unless the two be compressed and held permanently together, as their natural and regular working positions, as herein shown, and independent, in their supporting-power, of any outside weight, excepting contact, to hold on by.

The invention of any "wedging arrangement of rollers," or "clamping of rollers, by pressure from the casing," or "friction from weight of sash," or "vertically" or "horizontally-moving bearings and clamp," I distinctly disclaim.

The compressed rollers, moving uniformly together with immovable bearings, comprise my invention in that direction, as herein shown.

Claim.

I claim the arrangement of the elastic roller D and D', combined with the smaller roller F, compressed into the elastic covering of the former, and secured in that position between the plates A B, &c., substantially as described herein.

R. B. HUGUNIN.
